UNITED STATES PATENT OFFICE.

EDWIN H. MARTIN AND JOHN BEAVIS, OF CLEVELAND, OHIO.

ROLLING-MILL.

SPECIFICATION forming part of Letters Patent No. 349,730, dated September 28, 1886.

Application filed June 5, 1886. Serial No. 204,196. (No model.)

To all whom it may concern:

Be it known that we, EDWIN H. MARTIN and JOHN BEAVIS, citizens of the United States, residing at Cleveland, county of Cuyahoga, and 5 State of Ohio, have invented certain new and useful Improvements in Rolling-Mills; and we do hereby declare the following to be a description of the same, and of the manner of constructing and using the invention, in such full, 10 clear, concise, and exact terms as to enable any person skilled in the art to which it appertains to construct and use the same, reference being had to the accompanying drawing, forming a part of the specification, the principle of the 15 invention being herein explained and the best mode in which we have contemplated applying that principle, so as to distinguish it from other inventions.

The object of this invention is to provide an 20 improvement in the construction of rod-mills, whereby a first-class quality of rod may be rolled in large output with economical expenditure of fuel. In carrying out this object we employ a billet-train, a continuous train, 25 and a rod-train, the three trains being driven by one engine, which is a compound engine, the continuous train having its several roll-passes in line with the last pass of the billet-train and the first pass of the rod-train, the 30 rod-train having its consecutive rolls divided off in sections, each section having the rolls contained therein of less diameter than the diameter of the rolls of the preceding section, and each section being independently geared 35 to an underground driving-shaft by gearing which drives each succeeding section at a faster speed than the immediately-preceding section, said speeding up of the rod-train sections being of character sufficient to keep the overplus 40 close to the rolls, while said reduction of diameter of the section-rolls insures clean-shaped rods, without fins or long shoulders.

The drawing is a plan view of the mill, wherein A represents a compound engine located to the left of billet-train B, and to the driving-shaft of which the shafting of said train is directly geared. This first train, B, we use as an eighteen-inch train, three-high rolls, and a trough, C, extends from the last 45 roll-pass of said train to the first roll-pass of the continuous train D. This second train

has the several shaftings, E, of its stands of rolls bevel-geared to shaft F, which latter is bevel-geared to shaft G, connected by belt H to the driving-shaft of engine A, shaft 55 G being located forward of and parallel with the billet-train, while the two-high-roll stands of the continuous train are located between and in line with the last stand of the billet-train and the first stand of the rod-train. The 60 rod-train J is subdivided into sections, three-high rolls, the first section having one stand of rolls, the second section having two stands of rolls, the third section having three stands of rolls, the fourth section having two stands 65 of rolls.

A rotary shaft, L, extends underground parallel with the rod-train, said shaft spur-geared at its forward extremity to shaft G by gear-wheel a on the latter shaft, meshing with gear-wheel b on shaft L. The shafting M of the first section of the rod-train is coupled directly to and driven by shaft G. The shafting N of the second section of the rod-train is spur-geared to shaft L by gear-wheel c on the latter, 70 meshing with gear-wheel d on said shafting. The shafting P of the third section of the rod-train is spur-geared to shaft L by gear-wheel e on the latter, meshing with gear-wheel f on said shafting. The shafting R of the fourth 75 section of the rod-train is spur-geared to shaft L by gear-wheel g on the latter, meshing with gear-wheel h on said shafting. Gear-wheel d is of less diameter than gear-wheel a, while gear-wheel f is of less diameter than gear-wheel d, and gear-wheel h is of less diameter than gear-wheel f. Gear-wheel c is of greater 80 diameter than gear-wheel b, while gear-wheel e is of greater diameter than gear-wheel c, and gear-wheel g is of greater diameter than gear-wheel e—that is, the gear-wheels which are fixed on the respective shaftings of the several train-sections decrease in diameter as we 85 go down the train, while the respective gear-wheels which are fixed on the driving-shaft L increase in diameter as we go down the train; hence the second train-section is speeded at a 90 faster rate than the first section, while the third section is speeded faster than the second section, and the fourth section is speeded still 95 faster than the third section.

The several stands of rolls in the rod-train

have the diameters of their rolls decreased as we go down the train. This decrease in roll-diameter operates in conjunction with the increase in speed as we go down the rod-train, 5 and the two are so graduated in reference to the decreasing diameter of the rod being rolled that all the loops or overplus of the rod are taken up close to the rolls, instead of being permitted to run out over the floor, and thereby 10 cooled.

Each successive increase of speed takes place where the oval rod from the preceding pass enters the next square pass, and this square rod enters the next oval pass through the well-known repeater. The last roll-pass in the 15 third section of the rod-train may be used as a finish for No. 5 or 6 rod, while the fourth section is employed when rolling Nos. 7 and 8 rod.

We claim—

The combination of engine A, billet-train B, 20 continuous train D, sectional rod-train J, shafts F G L, and the described intermediate mechanism connecting said parts together as they are operated by the one engine and in the manner set forth, all substantially as and for the purpose described. 25

In testimony that we claim the foregoing to be our invention we have hereunto set our hands this 24th day of May, A. D. 1886.

EDWIN H. MARTIN.
JOHN BEAVIS.
